United States Patent Office

Des. 183,771
Patented Oct. 21, 1958

183,771

HANDLE

Paul J. Schwind, South Bend, Ind., assignor to Kawneer Company, Niles, Mich., a corporation of Delaware

Application September 16, 1957, Serial No. 47,752

Term of patent 7 years

(Cl. D10—8)

Fig. 1 is a perspective view of a handle, showing my new design;

Fig. 2 is a front elevational view of the handle of Fig. 1;

Fig. 3 is a side elevational view of the handle of Fig. 1; and

Fig. 4 is a top plan view of the handle of Fig. 1.

I claim:

The ornamental design for a handle, substantially as shown.
